UNITED STATES PATENT OFFICE

155,767

DESIGN FOR A BUMPER GUARD OR SIMILAR ARTICLE

Richard H. Arbib, Grosse Pointe Woods, Mich., assignor to Houdaille-Hershey Corporation, Detroit, Mich., a corporation of Michigan

Application March 30, 1948, Serial No. 145,448

Term of patent 7 years

(Cl. D14—6)

To all whom it may concern:

Be it known that I, Richard H. Arbib, a citizen of the United States and a resident of the city of Grosse Pointe Woods, in the county of Wayne and State of Michigan, have invented a new, original, and ornamental Design for a Bumper Guard or Similar Article, of which the following is a specification, reference being had to the accompanying drawing, forming a part thereof.

On the drawing:

Figure 1 is a front elevational view of the bumper guard or similar article, showing my new design;

I claim:

The ornamental design for a bumper guard or similar article, as shown.

RICHARD H. ARBIB.
